UNITED STATES PATENT OFFICE

2,359,791

LIQUID COOLING APPARATUS

Albert A. Ralston, Fort Wayne, Ind., assignor to
 General Electric Company, a corporation of
 New York

Application March 2, 1943, Serial No. 477,721

8 Claims. (Cl. 62—141)

My invention relates to liquid coolers and the like, and particularly to mechanically refrigerated drinking water coolers.

One type of liquid cooler frequently employed for cooling drinking water comprises a chamber or container for holding a body of water in heat exchange relation with a refrigerant evaporating unit of a mechanical refrigerating machine. Good heat exchange between the refrigerant evaporating unit and the body of water is necessary in order that the water may be cooled at a rate commensurate with the rate of use of the drinking water. High rates of cooling may be obtained by employing containers constructed of metal. However, there may be objections to the use of metal because of difficulty in cleaning and liability to corrosion. More expensive metals such as stainless steel avoid some of these objections; however, a container constructed of ceramic material such as vitreous china is very easily cleaned and may be made acid-proof. The difficulty encountered in the construction of a cooling unit including a ceramic chamber lies in obtaining adequate heat exchange between the refrigerant evaporating unit and the water in the container and in assembling the refrigerant evaporating unit on the container. Accordingly, it is an object of my invention to provide a liquid cooler or the like including an improved liquid cooling unit constructed of ceramic material.

It is another object of my invention to provide a water cooler or the like having a ceramic cooling chamber and including an improved arrangement for securing a refrigerant evaporating unit to the chamber.

It is a further object of my invention to provide an improved method for constructing liquid coolers or the like including cooling chambers of ceramic material.

Further objects and advantages of my invention will become apparent as the following description proceeds and the features of novelty which characterize my invention will be pointed out with particularity in the claims annexed to and forming a part of this specification.

For a better understanding of my invention, reference may be had to the accompanying drawings in which Fig. 1 is a sectional side elevation of a drinking water cooler embodying my invention; Fig. 2 is a perspective view of a cooling unit shown in Fig. 1 with the cooling chamber and refrigerant evaporating coil separated for purposes of illustration; and Fig. 3 is a sectional side elevation of a portion of a water cooler illustrating another embodiment of my invention.

Briefly, the water cooler shown in the drawings comprises a mechanical refrigerating machine arranged within a suitable casing and including a cooling unit comprising a refrigerant evaporating coil and a ceramic container for holding a body of water in heat exchange relation with the coil. The control for operating the refrigerating machine includes a thermal element arranged within a tube or well located in a recess formed in the container. The refrigerant evaporating coil is wound around the container and holds the thermal well in position; at least two of the turns of the coil are soldered or otherwise suitably bonded to the thermal well and the tightly wound coil is thereby held securely in its position on the ceramic container. The entire assembly is preferably dipped in a suitable bonding material such as an asphalt compound which protects the refrigerant tubing from corrosion and increases the rate of heat transfer between the tubing and the container.

Referring now to the drawings, the water cooler illustrated in Fig. 1 comprises a casing 10 secured on a supporting structure including a plurality of posts 11. Posts 11 are secured together rigidly at their lower ends by a plurality of rings 12 which constitute air inlet louvers, the casing 10 being supported on the top one of the rings 12. A refrigerating machine comprising a motor-compressor unit 13, a condenser 14, and a cooling unit 15 is supported on the posts 11. The condenser 14 includes an outer ring 16 which is welded to the posts 11, and an annular surge chamber or receiver 17 is provided between the compressor unit 13 and the condenser 14 and is welded or otherwise suitably secured to the posts 11. The receiver 17 also serves as the mounting support for the motor-compressor unit 13. The cooling unit 15 comprises a ceramic container or chamber 20 about which is secured a refrigerant evaporating coil 21. The operation of the refrigerating machine to supply refrigerant to the coil 21 is effected by a control 22 including a thermal element 23 mounted in a tube or elongated thermal wall 24. The container 20 and the coil 21 are assembled within blocks of molded insulation 25 and 26; these blocks being held together by suitable straps 27. The cooling unit 15 is secured to the tops of the posts 11 by bars or straps 28 which pass through the insulating blocks 25 and 26 and are bolted to the tops of the posts.

Water is supplied to the container 20 from a suitable bottle or reservoir 29, and a rubber gasket 30 is provided to act as a seat for the bottle and to seal the space between the bottle and the cas-

ing 10 as well as the space between the casing and the container 20. An air vent (not shown) is provided in the gasket 30 to admit air to the container 20 so that water may be withdrawn therefrom through a drain connection 31 upon operation of a push button valve 32.

Liquid refrigerant is supplied to the evaporator 21 from the condenser 14 through a liquid line 35. The refrigerant expansion device is a capillary tube or restrictor 36 which is provided between the line 35 and the coil 21 to effect the necessary reduction in pressure. Refrigerant evaporated in the coil 21 rises and collects in a gas header 37 and is withdrawn from the header through a suction line 38 and returned to the compressor in the unit 13. The capillary tube 36 is wound about the suction line 38 to provide heat exchange between the entering and leaving refrigerant streams.

The above arrangement of the water cooler is described and claimed in a copending application Serial No. 470,814, filed December 31, 1942, in the names of Dean C. Rinehart and Albert A. Ralston and assigned to the same assignee as the present application.

It is obviously desirable to form the ceramic container 20 in as simple a shape as possible to avoid difficulties which might be encountered in molding and in handling. Accordingly, the container 20, as shown in Fig. 2, comprises a cylindrical chamber having an upper portion 39 and a lower portion 40 of reduced cross-section. In order to provide good heat exchange between the water within the container 20 and the refrigerant within the evaporator coil 21, it is necessary that good contact be provided between the coil and the container and that this contact be maintained throughout the life of the water cooler. The coil 21 is securely held about the container 20 by bonding at least the top and bottom turns of the coil to the thermal control tube 24, and a longitudinal recess 41 is formed in the container 20 to accommodate the tube 24.

During the manufacture of the cooling unit 15, the tube 24 is placed in the recess 41 and a length of tubing is soldered or otherwise suitably secured to one end of tube 24. Tube 24 is then clamped in any suitable manner to hold it within the recess 41 while the tubing is wound about the container 20 to form the required number of turns of the evaporator coil 21. When the last turn has been completed, it is soldered or otherwise suitably bonded to the tube 24. The clamping is then removed and the entire coil remains securely in place. Furthermore, the tube 24 is securely clamped between the turns of the coil 21 and the wall of the container along the recess 41, and is, therefore, in heat exchange relation with the evaporator coil 21 as well as with the container 20. Since the tube 24 is at a temperature determined both by the refrigerant evaporating coil 21 and the temperature of the water in the container 20, the thermal bulb 23 mounted therein is sensitive to a change in temperature of either the refrigerant or the water.

After the coil 21 has been assembled on the container 20 the container and coil may be dipped in a suitable bonding material such as an asphalt compound loaded with silica to provide a coating which will protect the evaporator tubing from corrosion and which by filling the spaces between the turns of the coil 21 and container 20 will decrease the resistance to the flow of heat from the evaporator tubing to the container.

In Fig. 3 I have shown my invention applied

to a pressure water cooler, that is a water cooler to which water is supplied from a source under pressure such as the city water mains. The general construction of the water cooler shown in Fig. 3 is similar to that shown in Fig. 1 and corresponding parts have been designated by the same numerals with addition of the letter "a."

The cooling unit 15a comprises a closed ceramic container 45 provided with top and bottom openings in which are arranged fittings 46 and 47 respectively. Within the fitting 47 is a passage 48 connected by a tube 49 to a clean-out connection 50 which is normally closed. The fitting 47 is secured in position within the bottom opening of the container 45 by an annular threaded member or nut 51 threaded on to the body of the fitting 47 and arranged to compress a resilient gasket 52 of rubber or of other suitable material and seal the bottom opening against the pressure within the container. The upper fitting 46 is provided with an inlet duct or connection 53 opening into the top of the container 45 and an outlet connection or conduit 54 extending to a point near the bottom of the container 45 and having an air vent 55 near the upper end thereof. The outlet 54 communicates with a drinking fountain bubbler 56 which is mounted on a china top 57. The china top rests on the open top of the casing 10a and a suitable resilient gasket 58 is provided between the top 57 and the upper edge of the casing. Water from the city mains is supplied through a connection 60 and passes through an inlet coil or tube 61 in heat exchange relation with a drain pipe 62; the inlet coil 61 and pipe 62 being helically wound and arranged about the container 45 but spaced therefrom. The upper end of the coil 61 is connected with the inlet duct in the fitting 46. The fitting 46 is provided with an annular threaded member or nut 63 and a gasket 64 similar to those of the fitting 47; the fitting 46 thus seals the upper opening of the container 45 to prevent leakage of the water under pressure.

A suitable valve (not shown) is provided in the outlet connection 54 to control the discharge of water through the bubbler 56. When the valve is operated, water flows out of the bubbler 56 and an additional supply of water enters the container 45 through the fitting 46. A baffle plate 65 is rigidly secured to the fitting 46 as an integral part thereof and extends across the outlet end of the duct 53 so that water discharged from the duct 53 into the container 45 is distributed over the inner walls of the container which is cooled directly by the evaporator coil 21a. Waste water flows from a catch basin 66 in the top 57 through a drain connection 67 and into the drain pipe 62. The cold waste water flowing through the drain pipe 62 is thus brought into heat exchange relation with the fresh water in the pipe 61 and precools the fresh water.

The coil 21a is secured to the container 45 in the same manner as that in which the coil 21 is secured to the container 20. A longitudinal recess 70 is provided in the container 45 and the thermal member or well 24a fits within the recess 70 and is employed to secure the evaporator coil 21a to the container 45, the top and bottom turns of the coil being soldered to the tube 24a as indicated at 71 and 72 respectively. The tube 24a is thus rigidly clamped between the container 45 and the coil 21a; this assembly is then dipped in an asphalt compound to form a coating which is indicated at 73. A suitable drain connection 74 is provided for the drain pipe 62; and

the cleanout connection 50, water supply connection 60, and drain connection 74 are mounted in a common fitting 75 including a heat insulation member 76 fitted within an opening in the casing 10a.

From the foregoing it is readily apparent that I have provided a cooling unit for liquid coolers and the like which is of simple construction and which provides a practical arrangement for utilizing a cooling chamber constructed of ceramic material in a cooling apparatus employing a mechanical refrigerating machine.

While I have described my invention in connection with water coolers including mechanical refrigerating machines, other applications will be apparent to those skilled in the art. I do not therefore desire my invention to be limited to the particular constructions shown and described and I intend in the accompanying claims to cover all modifications within the spirit and scope of my invention.

What I claim as new and desire to secure by Letters Patent of the United States, is:

1. A liquid cooler or the like comprising a container constructed of ceramic material, said container having a recess formed in a wall thereof, a cooling element arranged about said container in heat exchange relation therewith and extending over said recess, means including a temperature responsive element for controlling the operation of said cooling element, said temperature responsive element being arranged in said recess and being held in direct heat exchange relation with said container and in direct heat exchange relation with said cooling element whereby the temperature of said temperature responsive element is determined jointly by the temperature of said cooling element and the temperature of said container.

2. A liquid cooler or the like comprising a container constructed of ceramic material, a cooling coil comprising a plurality of turns arranged about said container in direct heat exchange relation therewith, a tube of heat conducting material arranged in heat exchange relation with said container and said coil and extending transversely of said turns, said coil being secured to said tube whereby said coil is maintained rigidly in position about said container, and means including a temperature responsive element for controlling the operation of said cooling element, said temperature responsive element being arranged within said tube.

3. A liquid cooler or the like comprising a container constructed of ceramic material, said container having a longitudinal recess formed in a wall thereof, a cooling coil comprising a plurality of turns arranged about said container and over said recess and having said turns extending transversely across said recess, an elongated metal member arranged within said recess in contact with said container and with a plurality of said turns, and means for securing at least two of said turns rigidly to said metal member for retaining said coil tightly in position about said container.

4. A liquid cooler or the like comprising a container constructed of ceramic material, said container having a longitudinal recess formed in a

wall thereof, a cooling coil comprising a plurality of turns arranged about said container and over said recess and having said turns extending transversely across said recess, a tube arranged within said recess in contact with said container and with a plurality of said turns, and means for securing at least two of said turns rigidly to said tube for retaining said coil tightly in position about said container.

5. A liquid cooler or the like comprising a container constructed of ceramic material, a cooling coil comprising a plurality of turns arranged about said container in direct heat exchange relation therewith, a tube of heat conducting material arranged in heat exchange relation with said container and said coil and extending transversely of said turns, said coil being secured to said tube whereby said coil is maintained rigidly in position about said container, means including a temperature responsive element for controlling the operation of said cooling element, said temperature responsive element being arranged within said tube, and a coating compound covering said container and said coil for bonding said coil on said container.

6. A liquid cooler or the like comprising a container constructed of ceramic material, said container having an opening in a wall thereof, a fitting for said opening having an inlet connection for admitting liquid to said container and an outlet connection for withdrawing liquid therefrom, means including a resilient gasket and arranged to compress said gasket between said fitting and said container for securing said fitting to said container and for sealing said opening, said inlet connection opening into said container near the top thereof and said outlet connection opening into said container near the bottom thereof, and a baffle on said inlet fitting adjacent the end of said inlet connection for distributing about the inner walls of said container liquid admitted thereto through said inlet connection.

7. The method of securing a coil of tubing about a container constructed of ceramic material which comprises clamping an elongated metal member to the ceramic container, bonding a length of tubing to said member, winding said tubing about said container and over said member to provide the desired number of turns for the coil, and bonding the last turn of said tubing to said member to lock said tubing and said member on said container.

8. The method of constructing a cooling unit or the like including a cooling chamber having walls of ceramic material, which comprises providing a container constructed of ceramic material and having a longitudinal recess in the outer wall thereof, placing an elongated metal member in said recess, securing one end of a length of metal tubing to said member, winding said tubing about said container, while holding said member clamped in said recess to provide a plurality of turns of tubing about said container, holding said turns tightly wound about said container and bonding the last turn thereof to said member for locking said tubing in place about said container.

ALBERT A. RALSTON.
